UNITED STATES PATENT OFFICE.

WILLIAM THOMAS KENNETH CALTON, OF LONDON, ENGLAND.

FOUNTAIN-PEN.

1,257,804.

Specification of Letters Patent. Patented Feb. 26, 1918.

Application filed November 10, 1917. Serial No. 201,348.

To all whom it may concern:

Be it known that I, WILLIAM THOMAS KENNETH CALTON, a subject of His Majesty the King of England, and resident of London, Kingdom of England, have invented 5 certain new and useful Improvements in and Connected with Fountain-Pens, of which the following is a specification.

This invention relates to fountain pens in

- 10 which the nib is carried by a feed bar which is caused to reciprocate within the barrel or font by means of a rotary and non-slidable helically slotted sleeve and is fitted with a pin which extends through the helical slot 15 into a straight longitudinal slot.

In the improved pen provided by the present invention an external gland or end plug is directly secured to the rear end of the barrel or font, the sleeve is wholly contained 20 within said gland or end plug, and a straight longitudinal groove is formed in the gland or end plug. By this means the operating parts do not trespass upon the ink font, enabling the full capacity of the latter 25 to be used as a reservoir for ink and avoiding corrosion of said parts.

The invention will now be described with reference to the accompanying drawings, in which:—

- 30 Figure 1 is a partly sectional elevation of a fountain pen embodying the invention;

Fig. 2 is a partly sectional elevation of the nib controlling mechanism and the gland or plug detached from the barrel, and

- 35 Fig. 3 is a transverse section on the line 3—3 of Fig. 1.

In the construction shown the nib *a* and an ink feeding element *b* are fitted in a substantially cylindrical slotted or perforated 40 enlargement or stopper *c* which is fitted or formed on the front end of a feed bar *d* and is adapted to be reciprocated within the barrel or font *e* of the pen, and when projected in the manner hereinafter described, preferably 45 to seal the nozzle or front end of the barrel by means of its beveled end *f* seating on a beveled shoulder *g* formed on the barrel.

An open ended gland or plug *h* has one of its ends *i* screwed into or otherwise fitted 50 in the rear end of the barrel *e* and its interior face formed with a straight longitudinal groove *j*. A sleeve *k* rotatably mounted and wholly contained within the gland or plug *h*, is provided with a flange *l* at its front end adapted to butt against the inner 55 end of said gland or plug, is formed with a

longitudinal helical slot *m*, and has its rear end formed or fitted with a reduced shank *n*. The rear end of the feed bar *d* is slidably mounted in the sleeve *k* and is provided 60 with a transverse pin or projection *o* one end of which projects through the slot *m* in the sleeve into the straight groove *j* in the gland or plug *h*. A cork, india-rubber or other washer *p* is fitted around the shank *n* 65 of the sleeve *k* and within the rear end of the gland or plug *h*, and an operating ring or cap *q* is secured, such as by a cross pin *r*, on the rear end of said shank and bears upon said rear end of the gland and against the 70 washer to render the joint ink-tight. A cap *s* is employed to cover the font or nib end of the pen, said cap being held in place by a threaded connection, as shown in Fig. 1.

When the operating ring or cap *q* is 75 turned it causes the sleeve *k* to rotate in the gland or plug *h* and, owing to the engagement of the pin or projection *o* on the feed rod *d* with the slot *m* in said sleeve, said rod is caused to move axially and thus project the nib *a* out of the barrel *e* into the writing position, as indicated by dotted lines in Fig. 1, said rod being prevented from rotation with the sleeve by the engagement of the end of the pin or projection *o* with the 80 straight groove *j* in the gland or plug.

It will be appreciated that owing to the location of the sleeve *k* completely within the gland or plug *h*, the ink containing capacity of the barrel *e* is increased, the barrel is not weakened by having to be internally grooved, a small amount of material is required to manufacture the parts as the sleeve does not extend well into the barrel, and as the sleeve is operated within the 90 gland or plug, it and the feed bar *d* are not liable to become clogged with sediment. It will be observed that the flange *l* which is provided at the front or inner end of the sleeve *k* and fits against the inner or front 95 end of the gland *h*, constitutes in effect the bottom of the font or ink reservoir, closing the inner or front end of the groove *j* and preventing the ink from escaping down between the sleeve and the gland. Upon reference to Fig. 2, it will be noted that by unscrewing the gland or plug *h* from the barrel, the feed bar *d*, the stopper *c*, the nib *a*, as well as all the working parts contained within the gland or plug, are carried there- 100 by as a unit out of the barrel or font and may be replaced and applied in the same 110

manner. There is nothing within the barrel or font to obstruct or interfere with the removal or insertion of the said parts. A comparison between the length of the font or barrel and the length of the gland or plug, shows that the latter is less than one-third the length of the former.

What I claim is:—

1. A fountain pen comprising a barrel having a sealing shoulder at one end and internal threads at its opposite end, said barrel being of substantially uniform diameter from the threaded end to a point adjacent the sealing shoulder, an external gland having its inner end externally threaded to engage the threads of the barrel and projecting within the latter, a rotary and nonslidable sleeve mounted and wholly contained within said gland, an annular flange 15 provided on the front or inner end of the sleeve and abutting the inner end of the gland at its junction with the barrel, said flange being located within the barrel so as to close communication between the barrel 20 and the gland, a reciprocatory feed bar carrying a nib and an ink feeding element and constructed to coact with the sealing shoulder of the barrel, said feed bar having its other end received within said sleeve and 25 connected therewith so as to be reciprocated by the rotary movement of the sleeve, and

means provided on and closing the outer end of the gland and connected with the sleeve for rotating the same, said means serving to hold said flange in its abutting 35 relation.

2. A fountain pen comprising a barrel constituting the ink reservoir, an external gland directly secured to the rear end of said barrel, a rotary and nonslidable helically slotted sleeve mounted and wholly contained within said gland, a straight longitudinal groove formed in the gland, an annular flange on the inner end of said sleeve abutting the inner end of said gland 40 and closing said groove, a reciprocatory feed bar formed with a perforated enlargement carrying the nib and an ink feeding element and adapted to coact with the sealing shoulder in the barrel, a pin secured to said feed bar and extending through the helical slot into said straight groove, a shank on the rear end of the sleeve, an operating ring secured to said shank and bearing against and closing the rear end of the gland, and a 45 washer interposed within the rear end of the gland and between the latter and said ring, said ring serving to hold the flange in its abutting position.

In testimony whereof I have hereunto signed my name.

WILLIAM THOMAS KENNETH CALTON.
